UNITED STATES PATENT OFFICE.

CARL LOUIS LASCH, OF REUDNITZ, LEIPSIC, SAXONY, GERMANY.

WIRE-STITCHING MACHINE.

SPECIFICATION forming part of Letters Patent No. 391,252, dated October 16, 1888.

Application filed May 21, 1887. Serial No. 239,237. (No model.) Patented in England April 5, 1887, No. 5,063, and in Germany April 5, 1887, No. 42,748.

To all whom it may concern:

Be it known that I, CARL LOUIS LASCH, of Reudnitz, Leipsic, Saxony, Germany, have invented new and useful Improvements in 5 Wire-Stitching Machines, (for which Letters Patent of Great Britain, No. 5,063, and of Germany, No. 42,748, were granted me on the 5th day of April, 1887;) and I do hereby declare that the following is a full, clear, and exact de- 10 scription of the invention.

My invention has for its object to adapt wire-stitching machines for the manufacture of round or polygonal card-board boxes, and more especially for securing the bottoms of 15 such boxes to the sides by means of steel wire.

In the following description reference will be made to the annexed drawings, in which—

Figure 1 is a side elevation of a wire-stitching machine embodying my invention, while 20 Figs. 2 to 5 represent a suitable clinching apparatus on a large scale, Fig. 2 being a front elevation. Fig. 2^a is an elevation of the clinching device with the cover-plate removed, showing the clinching-levers in the act of engaging 25 a staple, the view showing, also, a box, partly in section, in position on the work-supporting disk, which is also partly sectioned; Fig. 3, a partly side elevation and partly vertical section, and Fig. 4 a plan of the same, the plate 30 being removed. Fig. 5 is a section along line W W of Fig. 2. Figs. 6, 7, and 8 represent sections of boxes which may be made by my machine. Figs. 9 and 10 are diagrammatic views of the box-corner and clinching levers, 35 showing the latter at the commencement and finish of the clinching operation, respectively.

The machine may be similar to that described in my United States Patent, No. 378,324, dated February 21, 1888, and in the specification 40 of the English Patent No. 16,137 of 1884, with the exception of the saddle and clinching apparatus, which are constituted as follows:

Instead of the vertically-movable saddle A, (shown in Figs. 12 and 13 of the English Patent, specification No. 16,137 of 1884, and in my 45 aforesaid United States Patent,) I employ a curved beam, T, carrying at the top a supporting-disk, P, and rigidly connected at the bottom with an upright arm or guide-plate, t. 50 This arm t is guided vertically by a sleeve, u, as shown in Fig. 1, or by other convenient

means, and pressed upward at the required moment by the motion of the wedge-shaped extremity of the horizontal rod v, operated by the lever V, Fig. 1. As in my previous machine, the extremity of the rod v is situated between a pair of friction-rollers, t' t'', the bearing of the lower roller being fixed during the operation of the machine, but having means for adjusting them as circumstances require, 55 while those of the upper roller are movable with the arm t. In the present case the roller t' has its bearings in a recess of the arm t, while the lower roller is held in a shackle, t'', provided with a screw-spindle, t', which allows 60 the roller t'' to be placed higher or lower by turning the hand-wheel t''. The beam T is shaped in cross-section, as shown by Fig. 5, and carries at the top the clinching mechanism, which is movable vertically between a 65 pair of guide-plates, g g', secured to its side by means of screws z z. The plate f, carrying at the top the clinching-plates e e, Fig. 2^a, is connected at the bottom with an oscillating lever, h, pivoted to the side of the beam T by means 70 of the screw z. This lever is connected by a pin or stud with the upper end of a rod, s, joined at the lower end to an angle-lever, r, having its fulcrum at the back of the beam T, 75 as shown in Figs. 3 and 4. The angle-lever r is in contact with the extremity of an adjustable screw-stud, p, secured to the operating-lever O.

As shown in Fig. 2, the upper part of the beam T is inclined and provided with a slotted 80 disk, P, partly or wholly carved at its circumference, and made exchangeable, so as to suit the shapes and sizes of the boxes to be made.

The plate P has a slot, as before mentioned, 85 through which the upper end of the beam T and the plates g g' emerge, so that the face of the beam T and the plates g g' are flush with the upper surface of the plate P, in order that the corner of the box being stitched will be at 90 a point over the clinching-levers midway between the upper ends of the latter. The plate P is secured to the beam T by means of a short angle-iron, p', secured to the bottom of the plate and to the side of the beam by means of 95 short screws, as shown.

Fig. 2^a shows the clinching-plates e e, piv-

oted to the sliding plate *f* by means of pins 2 2, adapted to have their upper ends separated when the bar *f* is lowered, by coming in contact with the oblique cam-faces *e' e'*, which 5 may be formed integral with one of the plates *g' g'*. The construction and operation of this mechanism, however, is exactly analogous to that which forms an important part of the subject-matter of my earlier patent aforesaid, and 10 will not, therefore, require a detailed description here.

The operation of stitching is as follows: The side or cylindrical part of the box *r²* or receptacle to be formed is placed endwise over the 15 beam *T*, as shown in Figs. 2 and 2^a, and the bottom of the box on the plate *P* in such a manner that the edge of the cylinder or side coincides with the edge of the bottom, or that one part slightly overlaps the other. There- 20 upon the staple is formed, in the usual manner, in the upper part of the machine and driven into the side and bottom of the box through the slot *r⁵* between the plates *g' g'* by the beam *T* being pushed upward against the staple-forming head *R*, which motion is caused by the wedge-shaped extremity of the rod *v* being drawn between the friction-rollers *t' t'*. The ends of the staple projecting into the interior of the box, as shown in Figs. 2^a and 9, 25 are now caught on the outside by the inner oblique faces of the levers *e e*, which are moved upward by the bar *f*, and during the further ascension of said bar the upper ends of the levers *e e* are forced toward each other by coming 30 in contact with the converging faces *r³*, which action will bend the ends of the staple to the position shown in Fig. 9. Now, as the upward motion of the box is continued still farther, the upper ends of the levers will come 35 together and strike upon the stop *r⁴*, which action will place the ends of the staple on the outside of the levers, whereby further upward motion of the latter will cause the staple ends to be pressed firmly against the side and 40 bottom of the box. It is of course understood that the bar *f* is operated, through the medium of the lever *h* and rod *s* and angle-lever *r*, by the operating-lever *O* pushing the screw-stud *p* into contact with the angle-lever *r*. After 45 one staple has thus been applied the beam *T* is again lowered, the box shifted on the plate *P* the distance of two staples, and the operation is repeated.

What I claim is—

1. The combination, with a staple-forming 55 head, *R*, the beam *T*, suitable means for imparting a vertical reciprocating motion to said beam, and clinching mechanism carried by said beam, of a work-supporting plate secured to the end of said beam and having a peripheral slot for the reception of the end of the beam and said clinching mechanism, substantially as set forth.

2. The combination, with a staple forming 65 head, *R*, the beam *T*, suitable means for imparting a vertical reciprocating motion to said beam, and clinching mechanism located at the end of said beam, of a work-supporting disk or plate secured to the end of said beam, with its edge over said clinching mechanism, and having a peripheral slot for the reception of the end of said beam, and the clinching mechanism, whereby the said end will be flush with the surface of said plate.

3. The combination, with a staple-forming 75 head, *R*, the obliquely-arranged beam *T*, suitable means for imparting a vertical reciprocating motion to said beam and the clinching mechanism, of a work-supporting disk or plate secured transversely to the end of said beam 80 and having a slot from its periphery inward for the reception of said beam and clinching mechanism, the rod *s*, the lever *h*, pivoted to said rod and clinching mechanism and also to beam *T*, the operating-lever *O*, having a stud 85 or projection thereon, and a pivoted angle-lever attached to the rod *s*, as set forth.

4. The combination, with the staple-forming head *R*, having an angular notch therein, of a vertically-movable beam, a plate secured 90 to the end of said beam at an angle equal to the angle of said notch, and having a slot in which the end of said beam fits, and clinching mechanism having upper faces at an angle corresponding to that formed by the beam and 95 plate and projecting flush with the end of said beam, substantially as set forth.

In testimony whereof I have signed this specification in the presence of two subscribing witnesses.

CARL LOUIS LASCH.
